SUCTION NOZZLE

Gustaf Einar Lofgren, Rye, N. Y., assignor to
 Electrolux Corporation, Dover, Del., a corpora-
 tion of Delaware

Application October 7, 1933, Serial No. 692,565

3 Claims. (Cl. 15—157)

My invention relates to suction nozzles for vacuum cleaners and more particularly to nozzles for picking up hairs or fibers which are relatively difficult to pick up with nozzles used for large surfaces. Dog hairs and lint are difficult to pick up merely by suction. Mechanical agitation is also ineffective for certain fibers, threads and the like. A combination of scraping and suction is practical, but scraping is not good for 5 rugs and particularly for certain rugs of fine quality because the scraping cuts off the rug. Furthermore, a tool or nozzle having teeth or other scraping means does not readily move on 10 many rugs, or at least not readily in one direction on a rug. The rug is sometimes so constructed that the nozzle moves readily in one direction but not in the other whereas normal nozzle movement is backwards and forwards.

The object of my invention is to provide a 20 nozzle for readily picking up lint, hairs, threads and the like without using mechanical agitation or scraping. To this end I use a smooth surfaced nozzle capable of gliding easily in any direction on a rug or other surface, regardless 25 of the fabric structure, and cause the air in small volume to have rotary movement, so to speak a cyclone effect, adjacent the surface to which the piece to be picked up is adhering. Thus the vortex twists the lint or other sub- 30 stance and the suction removes it.

The accompanying drawings illustrate the preferred embodiment of my invention.

Fig. 1 is a vertical central cross-sectional view of a nozzle embodying my invention and is 35 taken on the line 1—1 of Fig. 2;

Fig. 2 is a sectional view of the same nozzle taken on the line 2—2 of Fig. 1 and on the line 2—2 of Fig. 3;

Fig. 3 is a bottom view of the nozzle shown in 40 Figs. 1 and 2;

Fig. 4 is a view taken on the line 4—4 of Fig. 2;

Fig. 5 is a vertical cross-sectional view of another embodiment of the invention, taken on lines 5—5 of Figs. 6 and 7;

Fig. 6 is a cross-sectional view taken on the lines 6—6 of Figs. 5 and 7; and

Fig. 7 is a cross-sectional view taken on the line 7—7 of Fig. 5.

The nozzle 10 shown in Figs. 1 to 4 comprises 50 an oval-shaped base portion or shank 11 and an upper tubular portion 12. On the bottom of the base portion is a smooth contact surface 13. A central passage 14 intersects the contact surface 13 and passes through the tubular portion 55 12. The lower part of passage 14 adjacent the

contact surface 13 may be termed the mouth of the nozzle and the lower part of the surrounding structure, essentially the base portion 11, may be termed the lip or lip structure of the nozzle, which surrounds the nozzle mouth. The upper 5 or outlet part of the passage 14 is tapered or otherwise formed to receive and engage the end 15 of an air hose connected to a source of suction such as the fan of a vacuum cleaner. Passage 14 is preferably of circular cross-section as 10 shown. It will be seen that the outlet connection is of greater cross-sectional area than the mouth.

A plurality of grooves 16, which are preferably straight, are cut, cast or otherwise formed in 15 the bottom or contact surface 13 of the nozzle 1p. These grooves 16 extend from the vertical side wall of the base portion 11 to the passage 14. They open tangentially into the passage or mouth 14. The passage 14 may be tapered in- 20 wardly at the bottom.

The nozzle may be made of one piece and of any material such as aluminum, hard rubber, or a phenol condensation product. It is not essential that the bottom surface 13 be smooth but 25 this is preferred so that the nozzle will glide easily on the rug 17 or other surface or substance to be cleaned.

In operation, air is drawn through the passage 14 in the direction of the arrow A. The nozzle 30 being placed against the rug 17, air is drawn through the open-sided grooves in the direction shown by the arrows B. As this air passes through the grooves 16, it is in contact with the carpet or other material to be cleaned and can 35 pick up dust or dirt therefrom. The air enters the passage 14 tangentially from the grooves or channels 16 and consequently forms a vortex, the air rotating about and approaching the center of 40 passage 14. It will be seen that the lip provides a deflector for each air stream entering the nozzle, thereby assisting the forming of the vortex. This vortex is adjacent the carpet or surface 45 to be cleaned and the whirl of the air twists any hairs or fibers so that they are dislodged and taken up into the air stream which flows on helically into the upwardly extending passage 14. The lower end of the passage may be inclined as shown so that dust particles thrown outwardly due to centrifugal force can readily 50 pass upwardly in the passage 14.

Figs. 5, 6, and 7 show a duplex swivel nozzle embodying the invention. Attached to the hose end 15 is an elbow 20 having an internal passage 21 which corresponds to the upper part of the 55

passage 14 in the embodiment of Figs. 1 to 4. The elbow has an end piece 22 and is cut away at 23 to provide an opening for communication with either of the nozzle openings. The nozzle is provided with a large nozzle opening 24 and a smaller opening 25, which latter corresponds to the lower part of the passage 14 of the embodiment of Figs. 1 to 4. In the position shown in the drawings the interior of the elbow 20 is connected through the opening 23 with the vertical passage or bore 25. The passage 25 intersects the bottom smooth surface 13. This part of the nozzle is similar to that of Figs. 1 to 4. A plurality of grooves or channels 16 are formed in the bottom surface and communicate tangentially with the passage 25. The elbow 20 is provided with a boss 26 into which is screwed a screw 27, forming a pivot whereby the body of the nozzle is adapted to rotate on the elbow 20. One side of the nozzle is provided with a weight 28 whereby on lifting the nozzle from the floor the weighted side is moved downwardly by gravity and the nozzle can be readily turned around. On turning the nozzle around, the opening 23 provides communication between the passage 21 and the large nozzle opening 24 while closing the communication between the passage 21 and the passage 25. The operation of the smaller nozzle of this embodiment will be clear from the description of Figs. 1 to 4. In the structure shown in Figs. 5 to 7, the

nozzle opening 24 is used for ordinary rug cleaning and the nozzle is turned around to use the smaller opening 25 when it is desired to pick up a thread or the like which adheres to the carpet or other material being cleaned.

It will be understood that the invention is not limited to the structure shown and may be applied in a variety of forms to a variety of forms and sizes of nozzle. The invention is most effective, however, if used with a small nozzle opening.

I claim:

1. A suction nozzle having a mouth surrounded with a surface contacting lip, said lip being provided with grooves forming communications between the mouth and the atmosphere when the nozzle is in operative position, said grooves being so arranged that a single vortex of air will be produced in said mouth during the normal operation of the nozzle, said lip providing a deflector for each air stream entering the nozzle thereby assisting the forming of said vortex.

2. A suction nozzle as claimed in claim 1 in which the mouth is of circular cross-section and the grooves are tangential to the mouth.

3. A suction nozzle as claimed in claim 1 having an outlet connection of greater cross-sectional area than the mouth.

GUSTAF EINAR LOFGREN. 30
